APPARATUS FOR REMOVING STEAM FROM
GRINDERS

Frank W. Partsch, Jackson Heights, N. Y., assignor to J. O. Ross Engineering Corporation, New York, N. Y., a corporation of New York

Application January 29, 1934, Serial No. 708,724

1 Claim. (Cl. 83—75)

This invention relates to a method and apparatus for removing steam from paper pulp grinders.

In the operation of paper pulp grinders a large volume of steam is generated which is obnoxious and hazardous to the workmen in the room and undesirable by reason of its effect on other machinery and the building itself. Various attempts have been made to remove the steam by means of canopies or by exhausting the steam from the room and replacement by warm air.

Such methods have been costly in operation and at times inefficient. In addition, these methods were applicable to the old small capacity grinders of about six tons per twenty-four hours. A new type of pocket grinder has been developed having from twenty to forty tons capacity in twenty-four hours. The lath or jiggling device for roughing the stone is on the top instead of at the back where a removable cover or housing was sometimes utilized in previous types to remove the steam generated. With the new type of grinder an opening is necessary above the dam and this opening cannot be covered due to the necessity of continuous inspection during operation in order that slivers may be removed and to note the condition of the pulp. This opening permits the escape not only of the steam generated during the grinding but also the steam arising from the stream of pulp.

One of the objects of this invention is to provide a simple and efficient means for carrying off the steam generated during the grinding of pulp.

A further object of the invention is to remove the steam generated from the grinding of pulp from the point of generation to a predetermined delivery point.

A still further object of the invention is to remove the steam escaping from said opening by suitable means in order to permit continuous inspection through an opening on the outgoing side of the grinder.

Pocket grinders comprise a rotatable grindstone about which are radially placed a plurality of devices for holding blocks of wood to be ground into pulp against the grindstone.

In the older types an opening was left in the housing at the back to give access to the grindstone for the purpose of "jiggling" the stone and this opening was sometimes covered by a removable housing to remove the steam. In the new form the "jiggling" is done at the top and the removing of steam at that point is impracticable.

Referring to the drawing:

Figure 1 is a view principally in cross section

of a pulp grinder embodying the principles of my invention.

Figure 2 is a plan view of the steam removal means for two of said grinders.

Figure 3 is a detail sectional view of a housing for the purpose of removing steam to prevent leakage from the grinder housing taken on the line 3, 3, of Figure 2.

Figure 4 is a detail sectional view of the steam removal intake at the front or dam end taken on the line 4, 4, of Figure 2.

As the pulp grinder mechanism is not properly a part of this invention the specific description of the details other than required to describe this invention are omitted.

It should be borne in mind that during operation there is practically no air entering the outgoing end of the grinders and passing through the grinder to the box at the back. The grinder pockets are supported by columns 1 on a concrete base 2. Below the grindstone 3 is a pool 4 having a dam 5. Pistons 6 maintain the wood in contact with grindstone 3. Water is used in the grinding operation. The grinding of the pulp generates steam. A small amount of the steam is taken care of by housing 7 at the rear while the major portion of the steam emerges from the opening 8 at the outgoing or dam end of pool 4.

I have found that an open side chamber 9 connected by conduits 10 to an exhaust fan or other form of gaseous exhaust device 11 will collect and remove the vapor and steam issuing from the opening 8 above the dam. The preferable location of such exhaust chamber 9 is a short distance above opening 8 in order that there shall be an opportunity for the creation of a suction to contract and entrap the escaping steam. The relatively small amount of steam at the rear can be removed by conduits 13 connected to housing 7. Conduits 13 likewise connect with exhaust fan 11. In this way the steam may be removed and the structure is applicable to the various designs of pocket type pulp grinders that are now in use.

This invention has the further advantage of removing the steam from the mass of pulp as well as from the grinder, thereby reducing the annoyance of steam that otherwise might leak from the pulp delivery systems from the grinder as well as removing the steam from the grinding housings.

What I claim is:

The combination in a pulp grinder of the type having a rotatable stone mounted on a hori-

- zontal axis located above a pool to run with its peripheral portion in said pool, and a jiggling device at the top between front and rear radially located wood boxes, said pool being formed by
5 a dam and extending in front and rear of said stone, and there being an inspection opening between the top of the dam and bottom of said front wood box; a system of steam removal including a plurality of conduits connecting with
10 plural sources of steam generated by said stone in grinding and having interpolated in the system a fan for generating suction, the points of

entrance of steam into said system being respectively in advance and above said inspection opening adjacent the bottom of said front wood box, and behind the pool below said rear wood box, said steam entrance on the inspection opening side of the grinder comprising a chamber having an open side directed toward the pool, whereby steam and vapor rising from the pool along the lines of its natural flow is collected and exhausted through the system. 5 10

FRANK W. PARTSCH.
